RAILWAY SIGNALING SYSTEMS

Leon D. Dickinson, Omaha, Nebr., assignor to Westinghouse Air Brake Company, a corporation of Pennsylvania

Application August 8, 1950, Serial No. 178,321

2 Claims. (Cl. 246—34)

My invention relates to railway signaling systems, and particularly to a railway signaling system including a pair of line wires for supplying coded alternating current to the track rails of a stretch of track and also for governing a signal control relay at the entrance end of the stretch.

It has previously been proposed to provide railway signaling systems in which the track is divided into a plurality of block sections, each of which is provided with a wayside signal to govern the movement of traffic into the block section. Additionally, the block sections are each subdivided into a plurality of track sections, to each of which alternating current is supplied at times at the exit end thereof to govern train-carried cab signals on trains moving through the section. A pair of line wires extends the length of each block section and is arranged to have alternating current energy supplied thereto at the exit end of the block section in accordance with traffic conditions in advance of the block section. The alternating current energy is supplied to the rails at the exit end of the various track sections in the block sections by connections or taps to the line wires. Additionally, the wayside signal at the entrance end of the block section is governed by the energy supplied to the line wires at the exit end of the block section.

In previous systems of the type described, the apparatus is arranged in such manner that the failure of the alternating current energy supply would result in the interruption of the supply of energy for governing the train-carried cab signals and would also result in the interruption of the supply of energy for the control of the wayside signals. As a result, neither cab signals nor wayside signals would be operative, and train movements could not be made with the benefit of signal protection. Under certain conditions, it is desirable to permit the operation of trains in accordance with wayside signal indication, despite a failure in the supply of alternating current energy normally utilized for controlling the cab signals.

Accordingly, it is an object of my invention to provide a railway signaling system in which both wayside and train-carried signals are normally controlled by alternating current energy supplied over a wayside line circuit, and which system is arranged to provide control of the wayside signals alone from a standby source of direct current energy in the event of an interruption of the alternating current energy.

Another object of my invention is to provide a system of the type described, in which coded pulses of alternating current energy are normally supplied to a line circuit extending through a block section, and are supplied from the line circuit to the track rails of each track section in the block for the control of train-carried cab signals, and are additionally supplied to a signal control relay at one end of the block section to thereby reflect traffic conditions ahead, which system is arranged to supply direct current energy over the line wires to govern the signal control relay in the event of the failure of the alternating current energy supply.

2

Other objects of my invention and features of novelty will be apparent from the following description, taken in connection with the accompanying drawing.

In practicing my invention, I provide a pair of line wires extending the length of each block section in the stretch of railway equipped with a signaling system embodying my invention. At the exit end of the block section, coded alternating current energy is normally supplied to the line wires, in accordance with conditions ahead of the block section. At the exit end of each track section in the block section, the primary winding of a transformer is tapped to the line wires, and the secondary winding of the transformer is arranged to supply the coded alternating current energy of proper value to the rails of the track section to operate cab signal equipment on trains occupying the track section. At the entrance end of the block section, a transformer is connected to the line wires and supplies pulses of energy through a rectifier to energize the winding of a direct current signal control relay. Contacts of the signal control relay govern an associated wayside signal to thereby reflect conditions in advance of the block section. Additionally, there is provided at the exit end of the block section means responsive to a failure of the alternating current energy supply, for connecting the line wires to a standby source of direct current, governed by conditions ahead of the block section. At the entrance end of the block section, there is provided means for connecting the winding of the signal control relay directly to the line wires upon the failure of the A. C. energy, so that the signal control relay is then governed by the direct current energy supplied over the line wires in accordance with traffic conditions in advance of the block section. Moreover, the circuits may be arranged so that the line circuit, when operated on direct current, includes in series therewith, at the exit end of the block section, the winding of an approach lighting relay, so that the wayside signal is energized only when a train is approaching the signal to thereby conserve energy during the interruption of the alternating current energy supply.

I shall describe one form of railway signaling system embodying my invention and shall then point out the novel features thereof in claims.

The single accompanying drawing is a diagrammatic view showing a stretch of railway track and associated wayside circuits for a signaling system embodying my invention.

Referring to the drawing, there is shown a stretch of railway track having track rails 1 and 2, over which traffic moves in the direction shown by the arrow, that is, from left to right. The stretch is divided into block sections, such as the section X—O, and a wayside signal, such as 1S and 2S, is provided at the entrance end of each of the block sections to govern traffic entering the block section. Each of the block sections is divided into at least two track sections, such as the sections 1T and 1AT, by the insulated joints 3, and each of these sections is provided with a direct current track circuit comprising a track relay connected across the rails at the entrance end of the track section, such as relays 1TR and 1ATR, and a track battery connected across the rails at the exit end of the section such as batteries 1TB and 1ATB. The secondary winding of a track transformer, such as transformers 1TT and 1ATT, is connected in series with the track battery in a manner well known in the art, in order to superimpose coded alternating current upon the direct current track circuit energy, to operate train-carried cab signals. The primary windings of the track transformer are supplied with alternating current energy in a manner to be subsequently described.

It will be seen that front contact *a* of track relay 1ATR governs the supply of energy to track section 1T, in the

arrangement known in the art as a "relayed cut section" so that if either section 1T or section 1AT is occupied, the track relay 1TR will be released. The wayside signals, such as 1S and 2S may be of any type, and are shown as being of the well-known color-light type having a red lamp R, a yellow lamp Y and a green lamp G. The circuits for supplying energy to the signal lamps are arranged so that the red lamp R is lighted when the block section immediately in advance of the signal is occupied, the yellow lamp is lighted when the first block section in advance of the signal is unoccupied, but the second block section in advance is occupied, and the green lamp is lighted when the first two or more block sections in advance of the signal are unoccupied. The apparatus at the entrance end X of the block section X—O also includes a first signal control relay 1HR, a line power off relay 1LPOR, a rectifier 1LPRX, a line transformer 1LPT, and a condenser 1PQ, all of which provide for governing a second signal control relay 1DR by energy supplied over the line wires L1 and L2 extending from the entrance end X of the block section to the exit end O of the block section. The primary windings of the track transformers 1TT and 1ATT are connected to the line wires L1 and L2 through condensers 1TQ and 1ATQ, respectively.

At the exit end O of the block section, the apparatus includes two control relays 2HR and 2DR, governed by conditions in advance of signal 2S, an approach lighting relay 2AER, for governing the supply of energy to the lamps of signal 2S as will be subsequently described, a power off relay 2POR supplied with energy from a transformer 2PT through a rectifier 2PRX, and a coding device 180CT having contacts which are recurrently opened and closed at some specified rate, such as, for example, 180 times per minute. At each location, there is provided a source of direct current energy, such as the batteries 1LB and 2LB, the positive and negative terminals of which are designated by the reference characters B and N, respectively.

The apparatus is shown in its normal condition, with no trains occupying the block section X—O, and traffic conditions in advance of signal 2S such that relays 2HR and 2DR are picked up. Additionally, it is assumed that alternating current energy is being supplied at this time from the terminals BX and NX of a suitable source, not shown, to the primary winding 7 of transformer 2PT. The alternating current energy induced in the secondary winding 9 of transformer 2PT is rectified by the full wave rectifier 2PRX and the resultant direct current energy is supplied to the winding of relay 2POR so that the contacts of relay 2POR are picked up as long as alternating current is supplied to the primary winding 7.

Under the normal condition, energy is supplied to the green lamp G of signal 2S, by a circuit which may be traced from terminal B of the source, over front contact c of relay 2POR, front contact d of relay 2HR, front contact a of relay 2DR, and through the green lamp G to terminal N. Accordingly, the signal 2S displays a proceed aspect at this time.

With the power off relay 2POR picked up, the line wires L1 and L2 are connected to the secondary winding 9 of transformer 2PT over front contacts b and c of relay 2HR, front contacts a and b of relay 2POR, and the recurrently operated contact a of coding device 180CT. It will be apparent that, at this time, impulses of alternating current energy are supplied to the line wires L1 and L2 at the rate of 180 per minute.

Track relay 1ATR is energized by energy supplied over the track rails 1 and 2 of section 1AT from the battery 1ATB. Also, impulses of alternating current energy coded at the 180 rate are supplied from the line wires L1 and L2 to the primary winding 13 of transformer 1ATT through the condenser 1ATQ. The alternating current impulses induced in the secondary winding 15 of transformer 1ATT are superimposed on the direct current

energy supplied to the track section 1AT. Such a superposition of alternating current energy impulses upon direct current track circuit energy for the operation of train-carried cab signal or train control apparatus is well known in the art.

Since relay 1ATR is energized at this time, the track battery 1TB and the secondary winding 21 of transformer 1TT are connected in series across the track rails 1 and 2 of section 1T at the exit end of the section, over front contact a of relay 1ATR. The primary winding 19 of transformer 1TT is connected to the line wires L1 and L2 through the condenser 1TQ. Accordingly, impulses of alternating current energy supplied from the line wires as well as direct current from the battery 1TB are supplied to the rails of section 1T.

At the entrance end of the block section X—O, track relay 1TR is energized by the direct current energy supplied over the track rails from battery 1TB, and relay 1HR is energized by energy supplied over a circuit including front contact a of relay 1TR. Alternating current impulses are supplied from the line wires L1 and L2 to the primary winding 23 of transformer 1LPT through the condenser 1PQ. Impulses of alternating current energy induced in the secondary winding 25 of transformer 1LPT are rectified by the full wave rectifier 1LPRX and the resultant impulses of direct current are supplied to the winding of relay 1LPOR and to the winding of signal control relay 1DR by a circuit including front contact a of relay 1LPOR and front contact a of relay 1HR. The relays 1DR and 1LPOR are of the type which are slow in releasing their contacts, so that when the windings of these relays are supplied with direct current impulses from rectifier 1LPRX, the contacts of the relays will remain picked up during the short time intervals between the direct current impulses. At this time energy is supplied to the green lamp G of signal 1S by a circuit which may be traced from terminal B, over front contact b of relay 1HR, front contact a of relay 1DR, and through the green lamp G to terminal N.

From the foregoing, it will be seen that with the block section X—O unoccupied, and relays 2HR and 2DR picked up, the signals 2S and 1S display a green aspect and coded alternating energy is supplied to the rails of sections 1AT and 1T.

It will now be assumed that a train moving from left to right passes signal 1S and enters the track section 1T of the block section X—O. Accordingly, the track relay 1TR is shunted and its contacts release causing the relay 1HR to be released. When contact b of relay 1HR releases, it interrupts the circuit for supplying energy to the green lamp G of signal 1S and establishes an obvious circuit for supplying energy to the red lamp R of the signal. Additionally, when front contact a of relay 1HR releases, it interrupts the circuit for supplying energy to the signal control relay 1DR, so that relay 1DR releases. If the train is equipped with cab signal or train control apparatus responsive to alternating current impulses in the rails, it will be seen that the impulses of alternating current energy induced in the secondary winding 21 of transformer 1TT are supplied to the rails to influence the equipment, and in the usual manner with such apparatus, the supply of alternating current impulses at a rate of 180 times per minute will cause the signal apparatus to display a clear indication on the cab indicator.

When the train advances into track section 1AT, relay 1ATR is shunted and its contact a releases, interrupting the circuit for supplying energy from the battery 1TB and the secondary winding 21 of transformer 1TT to the rails of section 1T. At this time the cab signal or train control equipment is governed by the alternating current supplied to the rails of section 1AT from the secondary winding 15 of transformer 1ATT located at the exit end of section 1AT.

When the rear of the train vacates section 1T, no energy

will be supplied to the track rails 1 and 2 of the section since front contact *a* of relay 1ATR interrupts the circuit for connecting the track battery 1TB and the secondary winding 21 of transformer 1TT across the section rails.

When the train passes signal 2S, relay 2HR will release, the relay 2HR being controlled in a manner similar to relay 1HR. The front contact *a* of relay 2HR will interrupt the circuit for controlling relay 2DR, so that relay 2DR will also release. When contact *d* of relay 2HR releases, it interrupts the circuit previously traced for supplying energy to the green lamp G of signal 2S and establishes a circuit for supplying energy to the red lamp R of the signal, which circuit may be traced from terminal B over front contact *c* of relay 2POR, back contact *d* of relay 2HR, and through the red lamp R of the signal 2S to terminal N. When contacts *b* and *c* of relay 2HR release, the supply of alternating current impulses to the line wires L1 and L2 is interrupted and the back contacts of relay 2HR shunt the line wires. Accordingly, the supply of alternating current impulses from the secondary windings of the track transformers 1TT and 1ATT is discontinued, and similarly the supply of energy through the transformer 1LPT and the rectifier 1LPRX at the location of signal 1S is interrupted, so that relay 1LPOR releases its contacts. Relay 1DR is still released at this time, since relay 1TR is released, as a result of the train still occupying section 1AT of the block section X—O. When the rear of the train vacates section 1AT, energy from battery 1ATB flows over the section rails to the winding of relay 1ATR, and relay 1ATR picks up. When front contact *a* of relay 1ATR closes, the battery 1TB is connected across the rails of section 1T, to thereby supply energy over the section rails to track relay 1TR. When track relay 1TR picks up, the relay 1HR is energized and its front contact *b* establishes a circuit for supplying energy to the yellow lamp Y of signal 1S, which circuit includes a front contact *b* of relay 1HR and back contact *a* of relay 1DR.

At this time, with the train in advance of signal 2S, so that relays 2HR and 2DR are released, signal 2S will display a red aspect and the signal 1S will display a yellow aspect indicating "approach next signal prepared to stop." At this time, there are no alternating current impulses being supplied to the line wires L1 and L2, and as a result there is no alternating current energy supplied to the rails of track section 1T and 1AT, so that should a train pass the yellow signal 1S, the cab signal equipment on the train would not be influenced, and the cab indicator would display a restrictive indication, as is proper under these conditions.

If it is assumed that the signal 2S is governed by traffic conditions in the block in advance of the signals similar to the block X—O, then when the train in question clears the block in advance of signal 2S, the relay 2HR will pick up. When relay 2HR picks up, a circuit is established for supplying energy to the yellow lamp Y of signal 2S, which circuit may be traced from terminal B, over front contact *c* of relay 2POR, over front contact *d* of relay 2HR, and over back contact *a* of relay 2DR, and through the yellow lamp Y of the signal to terminal N. Additionally, when contacts *b* and *c* of relay 2HR pick up they reconnect the line wires L1 and L2 to the secondary winding of transformer 2PT through the recurrently operated contact *a* of the coding device 180CT and the front contacts *a* and *b* of relay 2POR. Accordingly, impulses of alternating current energy are again supplied to the line wires L1 and L2 at the rate of 180 impulses per minute.

The reestablishment of the supply of impulses of alternating current energy to line wires L1 and L2 causes the transformers 1TT and 1ATT to be recurrently energized, so that impulses of alternating current energy are supplied from the secondary windings of these transformers to their respective track sections, as was previously described.

The reestablishment of the supply of alternating cur-

rent impulses to the line wires L1 and L2 also causes energy to be again supplied to the transformer 1LPT at the entrance end X of the block section, and the energy from the secondary winding 25 of the transformer is rectified and supplied to the winding of relay 1LPOR, so that relay 1LPOR picks up its contacts *a* and *b*, and establishes the circuit for supplying impulses of direct current energy to the winding of relay 1DR. When relay 1DR picks up, its contact *a* establishes the previously traced circuit for supplying energy to the green lamp G of signal 1S. It will be seen therefore that at this time, the signal 2S is displaying a yellow aspect, the signal 1S is displaying a green or clear aspect, and coded alternating current energy is being supplied to the rails of track sections 1T and 1AT. Accordingly, a second train passing signal 1S at this time would receive a clear indication on cab signaling equipment carried by the train, in accordance with the traffic conditions.

When the train in question advances sufficiently far beyond signal 2S, the circuit for energizing relay 2DR will be completed in the conventional manner, over front contact *a* of relay 2HR and the line circuit for the block section in advance of section X—O, and when contact *a* of relay 2DR picks up it reestablishes the previously traced circuit for supplying energy to the green lamp G of signal 2S. At this time, therefore, the apparatus is restored to its initial condition as previously described.

It will now be assumed that, with the apparatus in its normal condition as shown, the source of alternating current energy supplied to the primary winding 7 of transformer 2PT is interrupted. As a result, rectified energy is no longer supplied through the rectifier 2PRX to the power-off relay 2POR, and this relay will release. When contacts *a* and *b* of relay 2POR release, they interrupt the circuit for connecting the line wires L1 and L2 to the secondary winding of transformer 2PT and establish a connection between the line wires L1 and L2 and the terminals of the battery 2LB, with the winding of a series approach relay 2AER interposed in the lead to the positive terminal B of the battery. The interruption of the supply of alternating current impulses over the line wires L1 and L2 cuts off the supply of rectified energy from the rectifier 1LPRX to the power off relay 1LPOR located at the entrance end of the section, and relay 1LPOR releases. When contacts *a* and *b* of relay 1LPOR are released, they establish a circuit for connecting the winding of signal control relay 1DR directly to the line wires L1 and L2 over front contact *a* of relay 1HR. At this time, therefore, energy is supplied to the windings of relay 2AER and signal control relay 1DR by a circuit which may be traced from terminal B of battery 2LB at the exit end of the block section, through the winding of series approach relay 2AER, over back contact *a* of relay 2POR, front contact *b* of relay 2HR, line wire L1, back contact *a* of relay 1LPOR, front contact *a* of relay 1HR, through the winding of relay 1DR, back contact *b* of relay 1LPOR, line wire L2, front contact *c* of relay 2HR, and back contact *b* of relay 2POR to terminal N of battery 2LB.

Accordingly, it will be seen that with the supply of alternating current energy at the exit end O of the block section interrupted, the line circuit comprising line wires L1 and L2 is energized by direct current energy, so that relay 1DR is now governed by the direct current energy supplied over the line wires. With relays 2HR and 2DR picked up, and track sections 1T and 1AT unoccupied, relay 1HR and relay 1DR establish the circuit for supplying energy to the green lamp G of signal 1S.

At the exit end of the block section, the lighting circuit for signal 2S now includes a back contact *a* of relay 2AER, and the back contact *c* of relay 2POR. With no train occupying the block section X—O, relay 2AER will be picked up, and accordingly the supply of energy to the lamps of the signal will be interrupted. Thus signal 2S is normally dark, so that the supply of energy from the

battery 2LB is conserved by keeping the signal lamps dark as long as no train is approaching the signal. Since in a conventional signaling installation, the battery 2LB would be a storage battery trickle charged by a rectifier normally supplied with alternating current from the source having terminals BX and NX, it is important to conserve the battery energy during interruption of the alternating current supply, by approach lighting the signals.

It will now be assumed that a train moving from left to right passes signal 1S and enters the track section 1T. As a result, relay 1TR is shunted to release the relay 1HR and its contacts *a* and *b* release. When contact *b* of relay 1HR releases it establishes a circuit for supplying energy to the red lamp R of signal 1S, and when contact *a* of relay 1HR releases it interrupts the circuit previously traced for energizing the signal control relay 1DR and the series approach relay 2AER at the exit end of the section. When relay 2AER releases, its back contact *a* establishes the lighting circuit for signal 2S, and since relays 2HR and 2DR are considered to be picked up at this time, the circuit is established for supplying energy to the green lamp G of signal 2S, which circuit may be traced from terminal B, over back contact *a* of relay 2AER, back contact *c* of relay 2POR, front contact *d* of relay 2HR, front contact *a* of relay 2DR and through the green lamp G of signal 2S to terminal N. Accordingly, the signal 2S is lighted in advance of the approaching train to provide the proper aspect.

It will be noted that during the time that the line wires L1 and L2 are energized with direct current energy due to the release of the power of relay 2POR, the direct current flowing in the line wires L1 and L2 is prevented from flowing through the primary windings of the track transformers 1TT and 1ATT, and the control transformer 1LPT, by the condensers associated with the transformers, so that there is no loss of direct current energy through the primary windings of the transformers.

It will be seen that at this time there is no supply of alternating current impulses to the track sections 1T and 1AT for the control of the cab signal of the train occupying these sections, but the direct current track circuit comprising the batteries and track relays operate in the same manner as previously described so that relay 1TR is released during the time that the train occupies the section X—O. When the train moves by signal 2S, relay 2HR will release, and its back contact *d* establishes a circuit for lighting the red lamp R of signal 2S, and its contacts *b* and *c* interrupt the supply of direct current energy to the line wires L1 and L2 and establishing a shunt across the line wires by means of the back contacts *b* and *c*. When the rear of a train vacates the block section X—O, track relay 1TR and in turn relay 1HR will pick up at the entrance end of the section, and front contact *b* of relay 1HR will establish a circuit in conjunction with back contact *a* of relay 1DR to supply energy to the yellow lamp Y of signal 1S. Although front contact *a* of relay 1HR is now closed in the control circuit for relay 1DR, relay 1DR remains released, since relay 2HR is released at the exit end of section X—O.

When the train advances sufficiently far to permit the relay 2HR to pick up, energy is again supplied to the circuit previously traced including the winding of relay 2AER, the back contacts of relay 2POR, the front contacts of relay 2HR and the front contact *a* of relay 1HR, so that relays 2AER and 1DR are again energized. When relay 1DR picks up, the circuit for supplying energy to the green lamp G of signal 1S is again established, and when relay 2AER picks up, its back contact *a* interrupts the supply of energy to the lighting circuits of signal 2S, so that the signal lamps are extinguished.

Should a following train pass signal 1S displaying a green aspect at this time, the relay 2AER will be released as previously described, and if it is assumed that the train in advance has not proceeded sufficiently far to permit the relay 2DR to pick up, when the back contact

a of relay 2AER releases, a circuit is established for lighting the yellow lamp Y of signal 2S over back contact *a* of relay 2DR.

When the supply of alternating current energy to the primary winding 7 of transformer 2PT is again established, the relay 2POR will pick up, and its contacts *a* and *b* will reconnect the line circuit to the secondary winding 9 of transformer 2PT over the recurrently operated contact *a* of coding device CT. Additionally, contact *c* again connects the lighting circuits for signal 2S directly to the direct current source so that the signal 2S is again continuously lighted. The supply of alternating current impulses to the track sections 1T and 1AT is reestablished, and the supply of alternating current impulses to the control transformer 1LPT at the entrance end of the section results in relay 1LPOR picking up to disconnect the circuit for relay 1DR from the line wires and connect it to the rectifier 1LPRX. The relay 1DR is therefore energized by the direct current impulses supplied from the rectifier 1LPRX, as previously explained. The apparatus is now restored to its normal condition, as shown in the drawing.

From the foregoing, it will be seen that my invention provides for the supply of direct current energy over the line wires which are normally used for the supply of alternating current energy to the track sections in the block section, the direct current energy being supplied to the line wires during the time which the supply of alternating current energy is interrupted, and the apparatus at the entrance end of the block section being arranged so that the signal control relay is normally governed by the presence of alternating current impulses in the line circuit, and is arranged to be connected directly to the line wires to be governed by steady direct current energy in the event of interruption of the alternating current impulses.

Although I have herein shown and described only one form of railway signaling system embodying my invention, it will be apparent to those skilled in the art that various changes and modifications may be made therein within the scope of the appended claims without departing from the spirit and scope of my invention.

Having thus described my invention, what I claim is:

1. In combination, a stretch of railway track divided into a plurality of track sections, a wayside signal for governing traffic entering said stretch, a track circuit for each of said track sections including a track relay and adapted to influence train-carried train control apparatus when supplied with coded alternating current energy, a line circuit governed by traffic conditions in advance of said stretch, a source of coded alternating current, a first and a second power off relay each having front contacts which are closed when coded alternating current energy is supplied to a winding of the relay and back contacts which are closed when the winding is deenergized, means including said front contacts of said first power off relay for connecting said line circuit to said source of coded alternating current energy, a source of direct current energy, means including said back contacts of said first power off relay for connecting said line circuit to said source of direct current energy, means for supplying energy from said source of alternating current energy to a winding of said first power off relay, a transformer for each of said track circuits having a secondary winding connected to the track rails and having a primary winding connected across said line circuit, a condenser for each of said transformers and connected in series with said primary winding to prevent the flow of direct current through said primary winding, a control transformer having a primary and a secondary winding, a condenser associated with said transformer, a rectifier, a signal control relay, said primary winding of said second transformer being connected to said line circuit through said associated condenser, means for supplying energy from said secondary winding of said con-

trol transformer to a winding of said second power off relay, circuit means including front contacts of said second power off relay for connecting the winding of said signal control relay to said secondary winding of said control transformer through said rectifier, circuit means including back contacts of said second power off relay for connecting the winding of said signal control relay directly to said line circuit, and means governed jointly by said track relays and said signal control relay for controlling said wayside signal.

2. In combination, a stretch of railway track divided into a plurality of track sections, a wayside signal for governing traffic entering said stretch, a track circuit for each of said track sections including a track relay and adapted to influence train-carried train control apparatus when supplied with coded alternating current energy, a line circuit governed by traffic conditions in advance of said stretch, a source of coded alternating current, a first and a second power off relay each having front contacts which are closed when coded alternating current energy is supplied to a winding of the relay and back contacts which are closed when the winding is de-energized, means including said front contacts of said first power off relay for connecting said line circuit to said source of coded alternating current energy, a source of direct current energy, means including said back contacts of said first power off relay for connecting said line circuit to said source of direct current energy, means for supplying energy from said source of alternating current energy to a winding of said first power off relay, a transformer for each of said track circuits having a secondary winding connected to the track rails and having a primary winding connected across said line circuit, a condenser for each of said transformers and connected in series with said primary winding to prevent
